MASK FOR CYLINDER MOLDS

Filed Feb. 14, 1930

UNITED STATES PATENT OFFICE

MILTON O. SCHUR, OF BERLIN, NEW HAMPSHIRE, ASSIGNOR TO BROWN COMPANY, OF BERLIN, NEW HAMPSHIRE, A CORPORATION OF MAINE

MASK FOR CYLINDER MOLDS

Application filed February 14, 1930. Serial No. 428,341.

This invention relates to paper making machinery, and more especially to mechanism for controlling locally the deposition of pulp on a cylinder mold so that the thickness of the web deposited on the mold may be varied 5 as desired from point to point on a transverse section of the web. To this end a flexible mask or apron is provided to cover part of that portion of the mold which is presented 10 to a pool of pulp stock. The mask is held against the mold by the pressure arising from the difference of level between the surface of the pool of stock and the surface of the white water within the mold. According to the invention, the end edge of the mask, which may 15 extend from one end of the mold to the other, is suitably shaped to vary as desired the amount of pulp deposited on the mold from point to point across the web. This control 20 may also be made adjustable by employing a mask which consists of a series of bands or ribbons laid edge to edge or overlapping. By separate longitudinal adjustment of these ribbons the end edge of the mask may be 25 varied readily to take different shapes.

For a more complete understanding of the invention reference may be had to the description thereof which follows, and to the drawings, of which,—

30 Figure 1 represents in section a pulp stock vat with a mask embodying the invention.

Figure 2 is an end elevation of the vat shown in Figure 1.

Figure 3 is a diagrammatic plan of the 35 end portion of a mask embodying the invention.

Figures 4 and 5 illustrate different shapes which can be given to the free end edge of a mask.

40 In Figure 1 of the drawings, a cylinder mold is conventionally indicated at 10, a pulp stock vat 11 being mounted against the mold so as to present its interior to an upper quadrant of the mold. To this end the bottom 12 45 of the vat extends up to or against the sur-

face of the mold. The vat is open at the end adjacent to the cylinder, and the side walls at this end have arcuate edge portions adapted to fit against the cylinder mold adjacent to the ends thereof. Within the vat 11 a pool 13 of 50 pulp stock is normally maintained during the operation of the mechanism by the introduction of a stream of stock through a suitable feed pipe 14. The normal level of the pulp stock may be maintained by an overflow 55 through a lateral opening 15, an adjustable dam 16 being provided within this opening so as to vary the level of the pool as desired.

Ordinarily the loading of pulp on the surface of the cylinder takes place on that portion of the surface which is presented to the pool, this being the portion extending from the bottom of the vat to the free surface of the pool. According to the invention, a mask 60 may be provided to cover a portion of the mold surface which is presented to the pool, this mask preferably extending from the bottom of the vat upwardly against the surface of the mold. By varying the heights to which this mask extends on the mold from point to 65 point across the vat, or lengthwise of the mold, the thickness of the web of pulp picked up by the mold may be locally varied from one edge of the web to the other. This mask may take the form of a flexible sheet 17 having 70 its free end edge suitably shaped as, for example, at 18 or 19 to vary the arc of mold surface exposed to the pool from point to point across the vat. Thus, for example, if the web picked up by the cylinder mold is 75 carried to a mandrel and wound thereon into the form of a tube, the thickness of the tube wall may be locally controlled from end to end as desired. By employing a mask such as is illustrated in Figure 4, the loading of 80 the cylinder mold would be heavier adjacent its ends than on the middle portion so that the ends of a tube wound from the pulp sheet thus picked up would be heavier than the middle portion. In like manner, by employ-

85 90 95

ing a mask such as is illustrated in Figure 5, a tube is produced having thinner walls near its ends than at its middle. Thus the local loading of pulp on the cylinder mold from end to end can be regulated by cutting the free end edge of the mask to any desired shape.

A more convenient way of exercising local control over the loading of pulp on the cylinder mold is by employing a mask such as is illustrated in Figures 1, 2 and 3. This mask comprises a plurality of strips 20 arranged edge to edge, preferably from one side of the vat to the other, or at least from one deckle on the cylinder to the other. Each of these strips has a free end portion 21 extending upwardly from a guide member 22, preferably located adjacent to the bottom 12 of the vat and also adjacent to the surface of the cylinder 10. The strips 20 may conveniently extend along the bottom of the vat, under a second guide member 23, and upwardly to some convenient point above the surface level of the pool 13. As shown in Figures 1 and 2, this end portion of each strip may be wound on a suitable drum 24 which, in turn, may be mounted on a rod 25. The frictional engagement of the several drums 24 with the rod 25 may be made sufficient to hold each strip in adjusted position. If desired, other suitable devices may be employed for this purpose. As shown, each drum 24 is adapted to be adjustably rotated by hand so as to shorten the upward extent of the free end portion 21 from the bottom of the vat or to lengthen the same so as to vary the area of mold surface covered by the free end of each individual strip. Thus by manipulation of the several drums 24 the strips 20 may be adjusted easily while the mold is in operation so that any local irregularities of thickness across the pulp web may be corrected if a web of uniform thickness is desired, or, on the other hand, any transverse variation of thickness of the web may be readily obtained.

One example of the latter is illustrated in Figure 3 wherein the outer strips 20 are retracted so that their free ends project up to a lesser height than those of the intermediate strips. The pulp web formed with such an arrangement of strips will have a zone of extra thickness extending in from each end for a definite length. If the pulp web is thereupon wound on a mandrel into a tube, the resulting tube has well defined integral flanges formed on its ends.

An embodiment of my invention having thus been described, it should be evident to those skilled in the art that many changes and modifications may be made therein without departing from its spirit or scope as defined by the appended claims.

I claim:

1. In combination with a vat adapted to

contain a pool of stock and a cylinder mold mounted to present a portion of its surface to a pool in said vat, a mask covering a part of said portion of surface, the arc of engagement of said mask with said surface being variable from point to point lengthwise of the mold.

2. In combination with a cylinder mold, and a pulp stock vat arranged to present a pool of pulp stock to a portion of the circumference of said mold, a mask within said vat extending upwardly from the bottom thereof against the surface of the mold, the upper edge of said mask having its upper edge shaped for local regulation of the thickness of the pulp web picked up by the mold from point to point across the web.

3. In combination, a cylinder mold, a pulp stock vat having its bottom and side walls fitted against the mold to expose an upper quadrant of the mold to the interior of the vat, a flexible mask within said vat extending upwardly against the surface of said quadrant from the bottom of the vat and terminating in a free end normally below the normal level for a pool of stock within the vat, successive portions of said free end of the mask extending upwardly to various heights against the mold.

4. In combination with a vat adapted to contain a pool of pulp stock, and a cylinder mold mounted to present a portion of its surface to said pool, a mask covering a part of said portion of surface, said mask comprising a plurality of strips arranged edge to edge to cover successive areas of said surface portion, said strips being independently adjustable to vary the extents of the several areas covered thereby.

5. In combination, a pulp stock vat, and a cylinder mold at one end thereof having an upper quadrant only of its surface exposed to the interior of said vat, a flexible mask for said mold, said mask comprising a plurality of strips arranged in side-by-side succession across the vat, each strip having a free end extending upwardly from the bottom of the vat against the surface of said mold to mask successive contiguous areas of said surface, and means for independently adjusting each of said strips to vary the arc of mold surface covered thereby.

6. In combination, a cylinder mold, a pulp stock vat fitted against an upper quadrant of said mold so as to present said quadrant to the interior of the vat, a guide member extending across the vat adjacent to the bottom thereof and adjacent to the surface of the mold, a second guide member extending across the bottom of the vat, said second member being spaced from and parallel to the first member, a plurality of strips of flexible material in edge to edge relation passing beneath said guide members, each of said strips having a free end portion extending

upwardly from the first guide member and masking a portion of the mold surface, each said strip also having an opposite end portion extending upwardly from said second guide member to a point above the stock 5 level in the vat, means for adjustably holding said opposite end of each strip to regulate the extent of its free end upward from the first guide member, and means for supplying pulp to said vat at a point between 10 said guide members.

In testimony whereof I have affixed my signature.

MILTON O. SCHUR.
